ROLLING HOOP CONTROL STICK

Salvatore C. Parrilla, Cleveland, Ohio

Application November 13, 1958, Serial No. 53,359

Term of patent 14 years

(Cl. D34—5)

Fig. 1 is a perspective view of a rolling hoop control stick showing my new design;

Fig. 2 is a fragmentary enlarged top plan view thereof;

Fig. 3 is a fragmentary enlarged side elevational view thereof taken at the lower side of Fig. 2;

Fig. 4 is an end elevational view thereof taken from the left end of Fig. 3; and

Fig. 5 is an enlarged side elevational view thereof taken at the side opposite Fig. 3.

The dominant features of my design reside in those portions shown in full lines on the drawing.

I claim:

The ornamental design for a rolling hoop control stick, as shown and described.
